UNITED STATES PATENT OFFICE.

HENRI VICTOR JULES JOUFFRET, OF NEUILLY-SUR-SEINE, FRANCE.

SPARKING PLUG.

1,368,160.

Specification of Letters Patent.

Patented Feb. 8, 1921.

Application filed June 10, 1918. Serial No. 239,251.

To all whom it may concern:

Be it known that I, HENRI VICTOR JULES JOUFFRET, a citizen of the French Republic, residing at Neuilly-sur-Seine, Department 5 of Seine, France, have invented certain new and useful Improvements in Sparking Plugs, of which the following is a specification.

This invention relates to sparking plugs for internal combustion engines.

10 It has for its object the construction of devices of the class in question in such a way that their cooling is effected in a more satisfactory and simple manner than it has hitherto been the case.

15 The invention consists generally in combining with the ordinary insulated electrode of the sparking plug, which is preferably formed from a highly resisting metal such for instance as nickel steel, a metal which is 20 a good conductor of heat.

The invention includes in addition to the principal constructional feature just mentioned, other features which will be described more fully hereafter.

25 It also comprises certain constructional embodiments including the said features, and as new articles of manufacture, sparking plugs made with the said improvements, as well as special parts for making up such 30 plugs.

In order that the invention may be clearly understood, I will now proceed to describe the same with reference to the accompanying drawing which is however given merely 35 by way of example.

Figures 1 and 2 of the said drawing are axial sectional views of sparking plugs made according to two methods of carrying out the invention.

40 In constructing the sparking plug for internal combustion engines, as illustrated in the drawing, I provide, in the usual manner a metallic casing *a*, adapted to constitute the electrode connected to the body of the

45 engine and to be screwed to the cylinder of the engine. I further provide an insulating body portion *b* adapted to be mounted in the said casing *a*. This may be made either as shown at Fig. 1, where the insulated electrode is introduced from the end of the casing which is not screwed into the cylinder of the motor, or else as shown in Fig. 2 where the insulated electrode is introduced through 50 the extremity of the casing which screws 55

into the motor cylinder, that is in one piece in the first case and in two pieces in the second.

The insulator *b* is provided with a central hole for the reception of the insulated electrode *c*.

In addition to, adopting the foregoing construction, according to my invention, I provide for the insulated electrode *c*, a rod which is preferably cylindrical and of a high resisting metal, such for instance as nickel steel. At the extremity of the said rod, for forming the electrode proper, I provide a central hole of relatively considerable length *c*¹, which I fill with a metal which is a good conductor of heat, such for instance as pure copper, and I further provide a sleeve *c*², also of metal which is a good conductor of heat, such as pure copper, adapted to be mounted at the other extremity of the rod *c*. For this purpose I prefer to provide on the said rod *c* a screw thread corresponding with an internal screw thread on the said sleeve *c*².

50 I mount the insulator *b* on the rod *c* in the ordinary way and then I place the sleeve *c*² in position.

I thus obtain a sparking plug with which the insulated electrode and the insulator are mounted in the casing *a* in one of the ordinary methods, but with which the cooling is insured by the conductivity of the metal inserted into the hole *c*¹ and by that of the sleeve *c*².

55 In addition, I prefer to make the sleeve *c*² of such length that it projects beyond the insulator and to provide fins *c*²⁰ upon the projecting portion to assist the cooling.

A nut *d* serving to hold the electrode in 60 the insulator also serves to keep the sleeve *c*² in position.

65 It will be understood that the particular methods of carrying out the invention just described may be varied and that the invention is only limited by a fair interpretation 100 of my claims.

Claims.

1. A sparking plug of the character described comprising an electrode of high resistance, an insulating member surrounding said electrode, and a sleeve of metal having a high coefficient of conductivity interposed between said electrode and said insulator member, said electrode having a lon- 105 110

itudinal recess within one end thereof and a metal plug of high conductivity positioned in said recess.

2. A sparking plug of the character described comprising an electrode of high resistance, an insulating member surrounding said electrode, and a sleeve of metal having a high coefficient of conductivity interposed between said electrode and said insulator member, said electrode having a longitudinal recess within one end thereof and a metal plug of high conductivity positioned in said recess, and said sleeve member projecting upward beyond said insulator member and having formed thereon annular flanges as described.

3. A sparking plug of the character described comprising an electrode of high re-

sistance, an insulating member surrounding said electrode, and a sleeve of metal having a high coefficient of conductivity interposed between said electrode and said insulator member, said electrode having a longitudinal recess within one end thereof and a metal plug of high conductivity positioned in said recess, said recess extending upward to within a short distance of said sleeve member.

In testimony whereof I have hereunto set my hand in presence of two subscribing witnesses.

HENRI VICTOR JULES JOUFFRET.
